UNITED STATES PATENT OFFICE.

FRED A. KÄDING, OF KRAMER, NORTH DAKOTA.

HAY-STACKER.

1,242,812.

Specification of Letters Patent.

Patented Oct. 9, 1917.

Application filed March 2, 1917. Serial No. 152,047.

To all whom it may concern:

Be it known that I, FRED A. KÄDING, a citizen of the United States, residing at Kramer, in the county of Bottineau and 5 State of North Dakota, have invented new and useful Improvements in Hay-Stackers, of which the following is a specification.

This invention relates to hay stackers of that general class or type which embodies a 10 frame structure, a load carrier and means for elevating the load carrier and for tilting the same to discharge the load in the desired direction, the load being placed on the carrier by a bull rake of ordinary construction.

15 The present invention has for its object to produce a device of the class specified wherein the load carrier will be guided for movement in a vertical plane instead of in an inclined plane as is customary, it being found that economies may thereby be effected 20 in space, structural material and in power required for the operation of the device.

25 A further object of the invention is to simplify and improve the general construction and arrangement of the frame structures including the tracks on which the load carrier is guided.

30 A further object of the invention is to simplify and improve the construction and operation of the load carrier and the means whereby the same may be tilted to a discharging position at the required point of its upward movement.

35 With these and other ends in view which will readily appear as the nature of the invention is better understood, the same consists in the improved construction and novel arrangement and combination of parts 40 which will be hereinafter fully described and particularly pointed out in the claims.

In the accompanying drawings has been 45 illustrated a simple and preferred form of the invention, it being, however, understood that no limitation is necessarily made to the precise structural details therein exhibited, but that changes, alterations and modifications within the scope of the claims may be resorted to when desired.

50 In the drawings,

Figure 1 is a view in front elevation of a hay stacker constructed in accordance with the invention, the load carrier being shown at the lowermost limit of its movement.

55 Fig. 2 is a side elevation showing the load

carrier at the upper limit of its movement and in a tilted or discharging position.

Fig. 3 is a rear elevation showing the load carrier in an intermediate position.

Fig. 4 is a top plan view showing the load carrier in its initial or receiving position.

Fig. 5 is a vertical sectional detail view taken on the line 5—5 in Fig. 1.

Fig. 6 is a sectional detail view through one of the upright track members and a portion of the load carrier, the same being taken on the line 6—6 in Fig. 2.

Fig. 7 is a perspective view illustrating a modified form of the tilting mechanism.

Corresponding parts in the several figures 70 of the drawings are denoted by like characters of reference.

The base or supporting frame of the improved machine has been shown as being composed of longitudinally disposed sills 15, 75 the same being spaced apart and connected together by cross bars 16, said sills and cross bars consisting of timbers of suitable dimensions to afford a support of the requisite strength and superficial area to firmly sustain the working parts of the frame in position for operation. The sills and cross bars are preferably mortised together at their respective points of intersection, and are bolted or otherwise firmly secured together. 80 The longitudinal sills 15 have been shown as being equipped at the front ends thereof with ground engaging wheels 17 to facilitate the moving of the machine from place to place. The base frame has also been shown 90 as being equipped with rings or eyes 18 through which stakes may be driven for the purpose of anchoring the frame in position for operation.

Supported on the base frame and extending upwardly therethrough are two track bars 19, said bars being disposed vertically and in spaced parallel relation. These track bars may consist of rods, tubular or otherwise, the lower ends of the same being externally threaded and fitted in correspondingly flanged sockets 20 of floor flanges 21 which are bolted or otherwise secured on the base frame, this form of construction avoiding the weakening of the base frame by mutilating the same to receive the lower ends of the track bars. The upper ends of the track bars are connected together and spaced apart by a cross bar or cap piece 23, the same being secured in position by means of nuts 105 110

24 for the reception of which the upper extremities of the track bars are externally threaded. Guy rods or braces 25 connect the upper end portions of the track bars 19 with the base frame with which the lower extremities of said guy rods or braces are suitably connected, preferably in such a manner as to enable them to be properly tensioned and adjusted to sustain the track bars in an upright or vertical position.

10 The load carrier comprises in its construction a pair of sleeves 26 slidably mounted on the track bars, said sleeves being provided at their lower ends with L-shaped coupling members 27 having laterally extending sockets 28, said sockets affording supports for a transverse shaft 29 whereby the coupling members 27 as well as the sleeves 26 are connected together and spaced apart in 15 such a manner as to be free to move vertically on the track bars 19. The load carrier further includes a bottom platform 30 and a rear wall or platform 31, said platforms being each composed of a plurality 20 of teeth or fingers 32 and 33, preferably made of wood, the same being securely mounted on metallic frame structures 34 and 35. The respective platforms are of 25 less width than the distance between the upright track bars, but the frame structure 30 of the rear wall or platform 31 includes 30 a cross bar 36 which is of sufficient length to abut terminally on the rear faces of the sleeves 26. The frame structure of the rear wall or platform 31 is provided with bearing sleeves 37 pivotally engaging the shaft 29, the cross-bar 36 serving as aforesaid to 35 limit the swinging movement in a forward direction of the wall or platform 31. The cross-bar 36 is connected with the frame structure of the bottom platform 30 by 40 means of inclined braces 38 whereby the rear wall or platform will be sustained in a position at an angle exceeding ninety degrees with respect to the bottom platform 30, which latter, in its normal or load receiving position, occupies an approximately horizontal position as will be best seen in 45 Fig. 1 of the drawings. Springs 39 are coiled on the shaft 29, each of said springs being terminally connected at one end with the shaft and at the other end with the frame structure of the rear wall or platform 31, the tension of said springs being exerted 50 to maintain said rear wall or platform in an upright position with the ends of the cross bar 36 in engagement with the rear sides of the sleeves 26.

Flexible hoisting elements such as ropes 60 or cables 40, two in number, are provided, each of said elements being terminally connected at one end with the bottom platform of the load carrier, near the rearward end thereof. The hoisting elements 40 are 65 guided over pulleys 41 which have been

shown as being suspended near the upper extremities of the track bars 19, the hoisting elements being subsequently guided over pulleys 42 which are mounted near the lower extremities of the track bars. The hoisting elements are subsequently joined together and connected with a draft element which has been shown as consisting of an ordinary evener or swingle tree 43.

44 designates an element which I call a 75 tilting frame, the same consisting of a frame made of a rod or wire in approximately triangular shape, the same having two limbs one of which, 45, is provided with an eye 46 pivotally engaging the shaft 29. The other limb 47 of the tilting frame is connected with the frame structure of the rear wall or platform of the load carrier. The tilting frame is formed intermediate the limbs 45 and 47 with a plurality of loops 48, 80 said loops being disposed one above the other in a vertical plane. Connected with the base frame is one end of a tilting rope 49, said rope having a plurality of stop members such as knots 50 which may be 85 formed or secured thereon at suitable intervals. This tilting rope is to be adjusted in one of the loops 48 of the tilting frame where, by reason of the stop members 50, it will be held securely in any position to 90 which it may be adjusted. The tilting rope 95 co-operates with the tilting frame to tilt the load carrier from its normal or receiving position to a discharging position at a predetermined point of the upward movement of said load carrier, it being readily understood that when the tilting rope becomes tensioned it will exert a downward pull on the tilting frame, thereby causing the platforms of the load carrier to be tilted 100 above the axis of the shaft 29 until the load receiving platform 30 occupies a substantially vertical position while the wall or platform 31 will be tilted in a downward and rearward direction as clearly seen in 105 Fig. 2 of the drawings, thus causing the load to slide from the load carrier in the direction of the stack. By proper adjustment of the tilting rope with respect to the tilting frame it will be seen that the discharging operation may be performed at 110 any predetermined point of the outward movement of the load carrier, thereby avoiding the necessity of lifting the load beyond the point absolutely necessary to insure the proper discharge of the load on the stack which is in process of formation. It will also be seen that a very minute adjustment may be effected owing to the presence of a plurality of loops 48 in the tilting 115 frame and a plurality of knots or stop members on the tilting rope, the rope being shifted from one loop to another of the tilting frame before passing to the next knot or stop member, thereby avoiding the 120 125 130

encumbering of the tilting rope with a large number of knots.

Instead of using the tilting rope 49 having stop members such as knots 50 it may be found desirable to use a chain such as illustrated in Fig. 7 where said chain is designated by 55, one end of said chain being connected with one of the loops 48 of the tilting frame 44. On the base frame there is provided a latch device such as a snap 56 with which one of the links of the chain 55 may be detachably connected, thereby enabling the operator to effect the desired adjustment in a very convenient and satisfactory manner.

From the foregoing description, taken in connection with the drawings hereto annexed, the operation and advantages of the improved hay stacker will be readily understood. It will be seen that owing to the vertical positioning of the track bars a machine may be constructed occupying much less superficial area than machines that are provided with inclined tracks. Considerable economies in structural material are also effected, and it will be found that the machine may be operated with slight expenditure of power. The machine may also be conveniently moved from place to place, and it is capable of being stored in small compass.

Having thus described the invention, what is claimed as new is:

1. In a machine of the class described, the combination with a pair of vertical track bars, of a load carrier mounted thereon for vertical movement, said load carrier comprising sleeves engaging the track bars, coupling members at the lower ends of said sleeves having laterally extending sockets, a shaft secured in said sockets, a tiltable element comprising a receiving platform and a discharging platform secured together in angular relation, said discharging platform having bearing members engaging the shaft and a cross bar that engages the sleeves to limit swinging movement of said platform in a forward direction, and a spring whereby the discharging platform is normally swung in a forward direction thereby positioning the receiving platform in a receiving position.

2. In a machine of the class described, a pair of vertically disposed track bars arranged in spaced parallel relation, a load carrier mounted for vertical movement on said track bars, said load carrier including track bar engaging sleeves, coupling members at the lower ends of the sleeves, a

transverse shaft secured in the coupling members, and a tilting element comprising a receiving platform and a discharging platform secured together in spaced angular relation, said element being pivotally mounted on the transverse shaft, means for swinging the tiltable element in a forward direction, means for limiting such swinging movement, a tilting frame secured on the tiltable element and having a plurality of spaced loops arranged in a vertical plane, and a flexible tilting element having one end secured to a fixed point of attachment and equipped with a plurality of stop members to engage the spaced loops of the tilting frame.

3. In a machine of the class described, a pair of vertically disposed track bars arranged in spaced parallel relation, a load carrier mounted for vertical movement on said track bars, said load carrier including track bar engaging sleeves, coupling members at the lower ends of the sleeves, a transverse shaft secured in the coupling members, and a tilting element comprising a receiving platform and a discharging platform secured together in spaced angular relation, said element being pivotally mounted on the transverse shaft, means for swinging the tiltable element in a forward direction, means for limiting such swinging movement, a tilting frame secured on the tiltable element and having a plurality of spaced loops arranged in a vertical plane, and a flexible tilting element having one end secured to a fixed point of attachment and equipped with a plurality of stop members to engage the spaced loops of the tilting frame, in combination with suitably guided hoisting elements for elevating the load carrier on the track bars.

4. In a machine of the class described, a base frame, vertical track bars mounted thereon in spaced parallel relation, a load carrier mounted for vertical movement on the track bars, said load carrier including a tiltable element, means for elevating the load carrier, and tilting means, the same including a tilting frame connected with a tiltable element on the load carrier and having a plurality of spaced loops arranged in vertical series, and a flexible tilting element one end of which is attached to the base frame, said flexible element having a plurality of stop members adapted to be adjustably connected with the loops of the tilting frame.

In testimony whereof I affix my signature.
FRED A. KAEDING.
